UNITED STATES PATENT OFFICE.

EMORY C. ANDREWS, OF CHICAGO, ILLINOIS.

PAPER-FASTENER.

No. 799,513.

Specification of Letters Patent.

Patented Sept. 12, 1905.

Application filed November 25, 1904. Serial No. 234,191.

To all whom it may concern:

Be it known that I, EMORY C. ANDREWS, a citizen of the United States of America, and a resident of Chicago, in the county of Cook 5 and State of Illinois, have invented certain new and useful Improvements in Paper-Fasteners, of which the following is a specification.

My invention relates to sheet-metal fastening devices for securing together a plurality of separate sheets of paper, and has particular reference to improving the construction of such fasteners for the purpose of increasing their range of usefulness and reducing their weight and the expense of making them. I accomplish these objects by the device shown in the accompanying drawings, in which—

Figure 1 is a plan of a paper-fastener constructed according to my invention. Fig. 2 is a transverse section of the same on the line 2 2 of Fig. 1. Fig. 3 shows the first steps of connecting a plurality of sheets of paper at one corner by means of a clip of the form 25 shown in Fig. 1. Fig. 4 shows the fastening in its closed form.

In the form shown in the drawings the paper-fastener consists of a substantially circular plate 3, of sheet metal, having a slot 4 extending across the same at one side of its center and terminating at points intermediate of and equally distant from opposite sides of the plate. The plate 3 has also a pair of branch slots 5 extending transversely from opposite ends of the slot 4 into the larger portion of the plate 3 and cutting therefrom the tongue 6, which is connected to the plate 3 at the ends of the branch slots 5 and which is free from said plate at its other end. The 40 slots 5 are wedge-shaped, having their wide ends adjacent to the slot 4. The inner edges 7 of the branch slots 5 are substantially parallel with each other, and their outer edges 8 are curved and converge toward each other 45 in the direction of the narrow ends of said branch slots 5. The edges 8 of the slots 5, as may be seen from the drawings, are so curved or bent as to lie substantially at right angles to each other at the points 9 near the 50 narrow ends of said slots and to more clearly approach parallelism at the points where said edges meet the slot 4. The edges 8 are also disposed eccentrically of the outer periphery of the plate 3 and are so arranged as 55 to approach said periphery most closely at points in alignment with the slot 4. The

plate 3 is preferably crimped at 10 along the line of the slot 4 to a circular transverse curvature, as shown in Fig. 2, to permit of closing the parts 11 and 12 of the plate 3 60 against each other without unduly straining the metal and weakening the same.

The fastener is adapted to be stamped complete in a single operation, the dies being so formed as to form the crimp 10 to bend 65 the tongue slightly out of the plane of the part 12 and to set the parts 11 and 12 at a slight angle to each other, as shown in Fig. 2.

The purpose of the wedge-shaped formation of the branch slots 5 is to permit of a 70 great range in the thickness of the sheets of material which are to be fastened together. It will be seen from Fig. 3 that when the fastener is placed over the corner of a plurality of sheets, with the tongue 6 on one side of 75 said sheets and the part 11 of the plate on the other side, then the sheets are not bent at all between the points 9 and the corner of the sheets. The slots 5 at the points 9 need therefore be only of sufficient width to accommodate the thickness of the pile of sheets. Between the points 9 and the slot 4, however, 80 the sheets are bent to a waved line over the sides of the plate 3 and under the tongue 6. The distortion of the sheets is greatest after 85 the plate is bent to its final form, as in Fig. 4, when the tongue assumes a position more nearly in the plane of the member 12. The part of the sheets which is opposite the tongue is forced out of the plane of the parts at each 90 side of the tongue. The greater width of the slots 5 at their junction with the slot 4 permits the fastener to be bent to its final form with a minimum distortion of said sheets. When the parts 11 and 12 of the clip are bent 95 upon each other, the parts 11 and 12 will lie closely against the opposite faces of the folded sheets, all of the bending taking place in the crimped parts 10 of the plate. The form of the slots which is shown in the drawings has another advantage over a mere U-shaped slot of uniform width in that the die for punching the former will be of great strength, even when formed with substantially parallel sides for a considerable distance from the cutting-face, thus greatly increasing the life of the machine for making the fasteners, and consequently decreasing the expense of manufacturing fasteners. 105

The operation of the device shown is as follows: The fasteners are delivered to the user in their open form, as shown in Figs. 1 and 2. 110

To apply one of the fasteners to a plurality of sheets of paper, the fastener is slipped over one of the corners of the pile of sheets with the tongue 6 and the part 11 on opposite sides of the sheets, as shown in Fig. 3. The part 12 is then bent down upon the paper opposite the part 11 to the position shown in Fig. 4, the crimping at 10 insuring that the fastener bends at those points. It will be readily seen that the fastener need not necessarily be used upon the corners of the sheets, but that a plurality of fasteners may be used for fastening together one of the edges of the pile of sheets by passing the tongue 6 over such edge and folding the sheets along the line of the slots 4 of the series of fasteners.

It will be seen that some of the details of the construction shown may be altered without departing from the spirit of my invention.

What I claim as my invention, and desire to secure by Letters Patent, is—

1. A paper-fastener comprising a thin plate having therein a main slot and having a pair of branch slots extending toward one side from said main slot to form a tongue between said slots, said branch slots being wedge-shaped and having their wide parts adjacent to the main slot, and the outer edges of said branch slots being arranged to converge toward the attached part of said tongue and to approach the periphery of the plate most closely at points substantially in alignment with the main slot, substantially as described.

2. A paper-fastener comprising a thin plate having therein a main slot and having a pair of branch slots extending toward one side

from said main slot to form a tongue between said slots, the outer edges of said branch slots being curved or bent and converging toward the attached part of said tongue and each being arranged to approach the outer periphery of the plate most closely at points substantially in alignment with the main slot, substantially as described.

3. A paper-fastener comprising a thin plate of substantially circular contour having therein a main slot and having a pair of branch slots extending toward one side from said slot to form a tongue between said slots, said branch slots being wedge-shaped and their outer edges being oppositely curved or bent and converging toward the attached part of said tongue, said branch slots being arranged eccentrically of the periphery of the plate and arranged to approach the periphery most closely at points near the main slot, substantially as described.

4. A paper-fastener comprising a thin plate having therein a main slot and having a pair of branch slots extending toward one side from said main slot to form a tongue between said slots said branch slots being wedge-shaped and having their wide parts adjacent to the main slot, said plate being crimped in alignment with the main slot to permit of being bent along said slot without weakening the metal through such bending, substantially as described.

Signed at Chicago this 23d day of November, 1904.

EMORY C. ANDREWS.
